DESIGN FOR AN ASHTRAY OR SIMILAR ARTICLE

Robert A. Kelly, East Pittsburgh, Pa., assignor to United States Glass Company, Pittsburgh, Pa., a corporation of Pennsylvania

Application January 31, 1938, Serial No. 74,733

Term of patent 3½ years

To all whom it may concern:

Be it known that I, Robert A. Kelly, a citizen of the United States, residing at East Pittsburgh, county of Allegheny, in the State of Pennsylvania, have invented a new, original, and ornamental Design for an Ash Tray or Similar Article, of which the following is a specification, reference being had to the accompanying drawing, forming a part thereof, in which

The ornamental design for an ash tray or similar article, substantially as shown.

ROBERT A. KELLY.
